ATTORNEYS

UNITED STATES PATENT OFFICE.

HARRY WEARNE, OF RIXHEIM, GERMANY.

DESIGN FOR WALL-PAPER.

SPECIFICATION forming part of Design No. 31,958, dated December 5, 1899.

Application filed November 11, 1899, Serial No. 736,693. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a full, clear, and exact description, reference being had to the accompanying drawing, forming a part thereof, in which is represented 10 a plan view of a strip of wall-paper embodying the features of my design.

The leading feature of the design consists of a group of poppies, the stems whereof appear to rise from a bed of apple-blossoms.

15 The detail features of the design consist of

the representation of poppies, the stems whereof rise vertically from a bed of apple-blossoms. Branches of apple-blossoms curve upward and in opposite directions from the bed, and sprays of the morning-glory vine are pendent from 20 the said upwardly-curved branches.

Having thus described my invention, I claim as new and desire to secure by Letters Patent—

The design for wall-paper as herein shown 25 and described.

HARRY WEARNE.
